UNITED STATES PATENT OFFICE

FRED M. HOWE, OF WELLSBORO, PENNSYLVANIA

PISTON

Application filed September 6, 1927. Serial No. 217,719.

This invention aims to provide a novel piston construction for an internal combustion engine, and, specifically, to improve the construction of the groove for the piston ring, the groove being widened at its inner end or side to form a chamber for oil, novel means being provided for conducting oil into the chamber as the piston reciprocates, and novel means being supplied for conducting the accumulated oil away, thereby preventing the oil from working into the combustion space of the internal combustion engine and fouling the engine with carbon.

It is within the province of the disclosure to improve generally and to enhance the utility of devices of that type to which the invention appertains.

With the foregoing and other objects in view which will appear as the description proceeds, the invention resides in the combination and arrangement of parts and in the details of construction hereinafter described and claimed, it being understood that changes in the precise embodiment of the invention hereinafter disclosed, may be made within the scope of what is claimed, without departing from the spirit of the invention.

In the drawings:—

Figure 1 shows in longitudinal section, a portion of the cylinder of an internal combustion engine, and a portion of a piston wherein the device forming the subject matter of this application has been embodied;

Figure 2 is a section on the line 2—2 of Figure 1;

Figure 3 is a longitudinal section showing a modification;

Figure 4 is a section on the line 4—4 of Figure 3;

Figure 5 is a section cut like Figures 1 and 3, but showing a modification.

As to the form depicted in Figures 1 and 2, there appears the cylinder 1 of an internal combustion engine, wherein the piston 2 is mounted for reciprocation. The piston 2 has a ring groove 3, and oppositely slanting walls 4 and 5, the walls forming a widened chamber 6 at the inner side of the ring groove. A ring 7 of the usual expansion type, or of any desired construction, is mounted in the ring

groove 3 and has contact with the wall of the cylinder 1. The piston 2 has a transverse passage 8 of approximately semi-circular form, the passage opening into the ring groove 3 and being located immediately adjacent to the ring 7, and on the crank case side thereof, that is, on that side of the piston ring which is remote from the combustion chamber of the internal combustion engine. The inner end of the passage 8 is in communication with the chamber 6, as the drawings clearly show. The piston 2 is cut away, by beveling, as at 9, at one corner of the ring groove 3, to collect oil and carry it into the passage 8. The piston 2 is supplied with an oil outlet for the chamber 6, the oil outlet being in the form of a bore 10 inclined with respect to the axis of reciprocation of the piston and discharging into the piston at the inner edge of the slanting wall 5.

In practical operation, the oil which finds its way toward the combustion chamber, between the piston and the cylinder, moves over the beveled surface at 9 and is carried by the passage 8 into the chamber 6, and as the piston reciprocates, the surplus oil is shaken out through the outlet 10, much as a liquid can be shaken out of an inverted and uncorked bottle that is reciprocated vertically in the hand of an operator. The operation is such that the oil is disposed of before it has an opportunity to work past the ring 7 and into the combustion chamber of the engine. There may be as many of the passages 8, and as many of the outlets 10 as is considered expedient, the same being distributed circumferentially around the piston 2 in spaced relation.

In Figures 3 and 4, parts hereinbefore described have been designated by numerals previously used, with the suffix "a". The oil outlet is in the form of a slot 11 formed in the piston 2 and intersecting the base of the passage 8^a, there being an undercut supplemental groove 12 in the piston 2^a at the outer end of the slot 11. There may be as many of the slots 11 as desired, and as many of the passages or recesses 8^a, and the groove 12 extends unbrokenly around the piston 2.

In Figure 5, parts hereinbefore described have been designated by numerals previously

used, with the suffix "b". The form under discussion is like the form shown in Figure 1, aside from the fact that the inclined wall 4 is done away with, and the beveling at 9 5 is replaced by a rectangular recess 14 which extends unbrokenly around the piston, like the beveling shown at 9.

What is claimed is:—

1. In a device of the class described, a piston 10 having a ring groove and oppositely slanting walls forming a widened chamber at the inner side of the ring groove, a ring in the ring groove, the piston having a transverse passage of approximately semi-circular form, the passage opening into the ring groove and being located immediately adjacent to the ring, on the crank case side thereof, the inner end of the passage being in communication with the chamber, the piston being supplied with an oil outlet for the chamber.
2. In a device of the class described, a piston having a ring groove and oppositely slanting walls forming a widened chamber 25 at the inner side of the ring groove, a ring in the ring groove, the piston having a transverse passage of approximately semi-circular form, the passage opening into the ring groove and being located immediately adjacent to the ring, on the crank case side thereof, the inner end of the passage being in communication with the chamber, the piston being supplied with an oil outlet for the chamber, the oil outlet being in the form of a slot 30 fashioned in the piston and intersecting the base of the passage.
3. In a device of the class described, a piston having a ring groove and oppositely slanting walls forming a widened chamber 40 at the inner side of the ring groove, a ring in the ring groove, the piston having a transverse passage, the passage opening into the ring groove and being located immediately adjacent to the ring, on the crank case side thereof, the inner end of the passage being in communication with the chamber, the piston being supplied with an oil outlet for the chamber.
4. In a device of the class described, a piston 50 having a ring groove and oppositely slanting walls forming a widened chamber at the inner side of the ring groove, a ring in the ring groove, the piston having a transverse passage, the passage opening into the ring groove and being located immediately adjacent to the ring, on the crank case side thereof, the inner end of the passage being in communication with the chamber, the piston being supplied with an oil outlet for the chamber, the oil outlet being in the form of a slot 55 fashioned in the piston and intersecting the base of the passage.

In testimony that I claim the foregoing as my own, I have hereto affixed my signature.
